UNITED STATES PATENT OFFICE.

CHARLES G. DELLENBACH, OF COLUMBUS, OHIO, ASSIGNOR TO THE JEFFREY MANUFACTURING COMPANY, OF COLUMBUS, OHIO, A CORPORATION OF OHIO.

CABLE CONVEYER.

1,321,811.

Specification of Letters Patent. Patented Nov. 18, 1919.

Application filed March 6, 1918. Serial No. 220,793.

To all whom it may concern:

Be it known that I, CHARLES G. DELLENBACH, a citizen of the United States, residing at Columbus, in the county of Franklin 5 and State of Ohio, have invented certain new and useful Improvements in Cable Conveyers, of which the following is a specification, reference being had therein to the accompanying drawing.

10 This invention relates to improvements in conveyers of the class in which each mechanism has an endless cable with spaced flights secured to the cable by attachment devices which also engage the teeth of the sprocket 15 wheels that guide and propel the conveyer.

The object of the invention is to provide an attachment for each flight which can be gripped to the cable so securely as to prevent any movement, transversely or longitudinally, of the attachment or of any of 20 its parts relatively to the cable, and which will not involve any deforming of the cable or throwing it or any of its strands into abnormal position.

25 The devices by which I attain this object are fully set forth in the following specification, reference being had to the accompanying drawings in which

Figure 1 is a fragmentary assembly view 30 of such a conveyer cable showing the relation of two attachments to the cable and to each other.

Fig. 2 is an elevational view of such an attachment taken along a plane transverse 35 of the cable.

Fig. 3 is a sectional view taken along the line 3—3 of Fig. 2.

Like numerals refer to similar parts in the several figures.

40 Referring to the drawing, the numeral 1 indicates a cable to which is secured at spaced intervals a series of attachments 2 adapted to be engaged by the teeth of a driving sprocket wheel to propel the cable 45 and to engage the material in a conveyer trough to move said material, in a manner well known in conveyer practice.

As shown, each of the attachments comprises two elements 3 and 4 adapted to 50 meet, and to be separated, at a plane longitudinal of the cable and remote from its periphery. The element 3 is considerably smaller, as an entirety, than that indicated by 4. Each is cast integral with the half 55 of a circular flight or scraper disk 6. The

larger attachment part 4 is formed with a longitudinal groove 7 of a depth considerably greater than the diameter of the cable and of a width such that its walls fit tightly against all of the lower half of the cable 60 surface. This element 4 of the attachment is also formed with a groove 8 in the transverse planes of the flight sections 6, 6; the depth of this groove being greater than that of the groove 7. 65

The smaller attachment element 3 has a longitudinal rib or tongue 10 fitting snugly in the groove 7 of the opposite element; the edge being concave to provide contact over all of the upper part of the surface of 70 the cable.

The flight section 6 of the element 3 has a straight inner edge which is transverse to, but lies in the plane of, the edge of the tongue 10. The edge part, indicated by 9, 75 serves as a tongue which can enter, and fits between the walls, of the groove 8 in the element 4.

When the parts of the attachment are brought together and held in working position the tongues 9 and 10 fit in the grooves 8 and 7 respectively. At 5, 5 there are bolts which pass through the attachment elements 3 and 4, and by which they are drawn powerfully together. When they are so drawn 85 the tongue 10 is caused to bear against the cable and the tongue 9 is forced into the groove 8. 80

The flight sections 6, 6 are constantly subjected to twisting and torsional strains; and as it is not practicable to have the bolts fitted in their apertures with perfect tightness these strains tend to cause slippings or shifting of the attachment elements upon each other and in relation to the cable. I 95 prevent this by utilizing the edge part at 9 of a flight section 6 as a locking tongue, and hold the two disk attachments against displacement preventing them from slipping transversely or longitudinally, relatively 100 to each other or to the cable.

It will be seen that I do not bend or crimp the cable; nor do I pass anything through it nor in any way deform it. The slippage of the flight on a cable from one 105 position to another, longitudinally, I have found to be due to the slight relative movements of the elements of the clamps, these movements being caused by strains, first in one direction and then in the other, from 110

the loads on the flight sections 6. By my improvement I hold the two flight sections of each element rigidly in their predetermined plane, and utilize the edge part 9 of one of them as a tongue to lock the two elements 3 and 4 of the attachment against relative movement.

What I claim as new and desire to secure by Letters Patent is—

- 10 In a cable conveyer, the combination with the cable of the larger attachment element 4 having an integral flight section 6 and the longitudinal cable groove of a depth greater than the diameter of the cable and 15 formed with the transverse groove in the

plane of the flight section and intersecting the cable groove, the smaller attachment element 3 with a longitudinal tongue adapted to fit in the cable groove in the larger element and having the integrally formed 20 flight section with its inner edge part 9 adapted to fit as a tongue in the aforesaid transverse groove, and the bolts for clamping the elements together.

In testimony whereof, I affix my signature, in presence of two witnesses.

CHARLES G. DELLENBACH.
